GOLF CADDY CART

Joseph Henry Gunning, Los Angeles, Calif.
Application May 13, 1958, Serial No. 50,865

Term of patent 14 years

(Cl. D14—3)

FIG. 1

The essential features of my design reside in those portions shown in full lines.

I claim:

The ornamental design for a golf caddy cart, substantially as shown and described.
